UNITED STATES PATENT OFFICE.

WILLIAM C. TREGONING, OF CLEVELAND, OHIO, ASSIGNOR TO THE TREGONING ELECTRIC MANUFACTURING COMPANY, OF CLEVELAND, OHIO, A CORPORATION OF OHIO.

ELECTRIC-LAMP SOCKET.

1,082,181.

Specification of Letters Patent. Patented Dec. 23, 1913.

Application filed May 13, 1912. Serial No. 696,862

To all whom it may concern:

Be it known that I, WILLIAM C. TREGONING, citizen of the United States, residing at Cleveland, in the county of Cuyahoga and State of Ohio, have invented certain new and useful Improvements in Electric-Lamp Sockets, of which the following is a specification.

This invention relates to electric lamp sockets, and the invention consists in the construction and combination of parts substantially as shown and described and particularly pointed out in the claims.

In the accompanying drawings, Figure 1 is a sectional elevation of the complete socket, and Fig. 2 is a sectional elevation of a portion of the socket at right angles to Fig. 1 and on the line of the key shaft. Fig. 3 is a plan view on a line corresponding to 3--3, Fig. 2. Fig. 4 is a side elevation of the body portion of the coupling and the screw socket thereon for the lamp. Fig. 5 is a central sectional elevation of Fig. 4. Fig. 6 is a plan of the switch plate shaped up for use and Fig. 7 is a plan of the blank plate. Fig. 8 is a cross section of the upper of the porcelain or like disks shown in Fig. 4. Fig. 9 is a side elevation of the switch plate. Fig. 10 is a cross section of the lower of the two porcelain members seen in Fig. 4 on the line of the groove for the key shaft. Fig. 11 is a perspective view of a spring conductor adapted to be affixed to the body part shown in Fig. 10 and to close the circuit on the lamp, not shown, as seen in Fig. 2.

The complete socket as shown in these views comprises two porcelain or like non-conducting body members 2 and 3, referred to hereinafter as disks for convenience of description, and the member 2 is also referred to as the upper disk and the member 3 as the lower disk for like reason. Both said disks necessarily have features of construction peculiar to the present invention and particularly to the adaptation of the new and original form of switch plate 4. The said plate is shown in Fig. 7 as struck up in blank from a piece of suitable flat plate, say copper or brass, and which is shaped originally as seen in Figs. 6 and 9, while its relation to or in the porcelain disks is seen in Figs. 1, 2 and 5. Respecting this plate, it is to be especially observed that it

is a single piece or part provided with a 55 spring switch tongue *a* of cross shape struck up from the middle of the plate lengthwise and end portions *b* and *c*, relatively at the ends of said tongue which provide the two bearings for the key spindle or shaft 6 while 60 a lip *d* is provided at the end and side of the said plate providing a terminal for the socket, the said portions *b*, *c* and *d* being bent at right angles to the body of the plate, as clearly seen in Fig. 9. The shaft 65 hole or bearing *c* for key spindle 6 is shown as more or less enlarged as compared with the shaft in cross section for reasons presently to be seen and slight recesses are formed oppositely in said hole *c* to permit the small 70 lugs *k* which are shown oppositely on the spindle 6 to pass through the same and which lugs enter between the lips 10 on the inside of said tumbler and cause it to rotate with the shaft, the engagement of said 75 parts however being comparatively loose within limits to allow freedom of movement between said parts. The said tumbler works in a recess formed partially in the two disks 2 and 3, and when the electric circuit is 80 closed the tumbler is turned to make contact with the said switch tongue *a* at one end and with the spring contact or conducting member 12 at the other end, thus closing the circuit upon the lamp. Otherwise, or 85 when the circuit is open, the tumbler lies cross-wise in its recess and out of electrical touch with at least one of said connections *a* and 12 so as to break the circuit. The lamp makes contact with the contact spring 90 12 as above indicated while the current is closed on switch plate 4 through its lip or ear *d* also as above described. The circuit is completed through the lamp by the shell socket 14, screw 15 and terminal or member 95 post 16.

From the foregoing it will be seen that only two screws 15 and 18, are required to bind the two disks 2 and 3 together and upon plate 4, and that there is no central 100 binding screw for said disks as formerly. In fact the present construction is such as to render a central screw unavailable as the plate 4 with its tongue lies bodily across the space between the two disks, and both disks 105 have about half each of the required recess *g* formed thereon for the rotation of tumbler 9 while disk 2 has an inclined slot *h* running

back from said recess to afford free play for the spring shank of said tongue, Fig. 2. The comparatively loose support of the tumbler on shaft 6 assures contact with the associate parts *a* and 12 at all times regardless of the strength of the spring in said parts. The tumbler shaft or spindle 6 has a washer *n* and is up-set more or less at its otherwise free end *m* to confine it in working position, and a suitable depression or groove *e* is formed in the disk or body member 3 to accommodate said shaft next beneath the plate 4 and which extends the bearing therefor. The sides of the plate 4 are also preferably recessed to avoid contact with screws 15 and 16, and when the plate is in place between the disks, its main body portion borders the recesses in the disks and is clamped firmly all around, while lateral and end movement of the plate is prevented by the portions *b*, *c* and *d*. A single switch plate as thus constructed simplifies the socket as a whole and makes it more durable and less likely to get out of working order. Moreover, it is distinguished from other devices known to me in that the spring and the bearing lips for the key spindle are projected in opposite directions and with the tumbler member adapted to pass through the plate

to engage contact parts on opposite sides of 30 the plane of the plate.

What I claim is:

1. In a key socket for electric lamps, a switch plate having a through opening between its borders and a spring tongue opposite said opening, in combination with a key spindle supported at one side of said plate and having a tumbler adapted to pass through said opening to the opposite side to engage said tongue. 40

2. A key socket for electric lamps comprising a one-piece switch plate having a spring tongue centrally therein and lips at its ends outside the ends of said tongue bent inward at right angles to said tongue and 45 having spindle supporting openings, in combination with a spindle projected through said openings, a tumbler thereon adapted to contact with said tongue and insulating members between which said plate is 50 clamped.

In testimony whereof I affix my signature in presence of two witnesses.

WILLIAM C. TREGONING.
